DESIGN FOR AN ASH TRAY

Frieda D. Hensley, San Francisco, Calif.

Application October 2, 1945, Serial No. 122,458

Term of patent 7 years

(CL. D85—2)

To all whom it may concern:

Be it known that I, Frieda D. Hensley, a citizen of the United States of America, residing at San Francisco, in the county of San Francisco and State of California, have invented a new, original, and ornamental Design for an Ash Tray, of which the following is a specification, reference being made to the accompanying drawing forming a part thereof.

Fig. 1 is a perspective view of an ash tray showing my new design and

Fig. 2 is a cross-sectional view, taken on the line 2—2 of Fig. 1.

I claim:

The ornamental design for an ash tray, substantially as shown.

FRIEDA D. HENSLEY.
